(57) **CLAIM**

The ornamental design for a ventilator, as shown and described.

DESCRIPTION

FIG. 1 is a front view of a ventilator according to my design;
FIG. 2 is a rear view thereof;
FIG. 3 is a top view thereof;
FIG. 4 is a bottom view thereof;
FIG. 5 is a right side view thereof; and,
FIG. 6 is a left side view thereof.

The broken lines showing environment or structure are for illustrative purposes only and form no part of the claimed design.
